(57) **CLAIM**

The ornamental design for a tillage point, as shown and described.

DESCRIPTION

FIG. 1 is a top right perspective view of a tillage point showing our new design;

FIG. 2 is a right side elevation view thereof, the left side elevation view being a mirror image thereof;

FIG. 3 is a top plan view of the tillage point;

FIG. 4 is a bottom plan view of the tillage point;

FIG. 5 is a front elevation view of the tillage point; and,

FIG. 6 is a back elevation view of the tillage point.

The broken line showing in FIGS. 2-4 and 6 is included for the purpose of illustrating portions of the tillage point and forms no part of the claimed design.
